(57) **CLAIM**

The ornamental design for a playing surface for spinning top toy, as shown and described.

DESCRIPTION

FIG. 1 is a front elevational view of a playing surface for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a rear, left-side, top perspective view thereof;

FIG. 8 is a rear, left-side, bottom perspective view thereof;

FIG. 9 is a front, right-side, top perspective view thereof;

FIG. 10 is a front, right-side, top disassembled perspective view showing the playing surface separated into four fasteners, a cover, a base, two small legs, two big legs, a rotary board, a connector, and a stick;

FIG. 11 is a rear, left-side, bottom disassembled perspective view, showing the playing surface separated into the four fasteners, the cover, the base, the two small legs, the two big legs, the rotary board, the connector, and the stick;

FIG. 12 is a cross-sectional view taken along the line 12-12 in FIG. 5;

FIG. 13 is a cross-sectional view taken along the line 13-13 in FIG. 5;

FIG. 14 is a perspective view of one of the fasteners;

FIG. 15 is another perspective view of one of the fasteners;

FIG. 16 is a perspective view of one of the small legs;

FIG. 17 is another perspective view of one of the small legs;

FIG. 18 is a perspective view of one of the big legs;

FIG. 19 is another perspective view of one of the big legs;

FIG. 20 is a perspective view of the connector;

FIG. 21 is another perspective view of the connector;

FIG. 22 is a perspective view of the stick; and,

FIG. 23 is another perspective view of the stick.

The broken lines depict parts of the playing surface for spinning top toy that form no part of the claimed design.

1 Claim, 16 Drawing Sheets
